Patented May 5, 1903.

UNITED STATES PATENT OFFICE.

EUSTACE CREEES AND CHARLES S. COURT, OF PROVIDENCE, RHODE ISLAND,
ASSIGNORS TO THE WATSON AND NEWELL COMPANY, A CORPORATION
OF RHODE ISLAND.

DESIGN FOR A HANDLE FOR SPOONS OR SIMILAR ARTICLES.

SPECIFICATION forming part of Design No. 36,303, dated May 5, 1903.

Application filed March 23, 1903. Serial No. 149,209. Term of patent 7 years.

To all whom it may concern:

Be it known that we, EUSTACE CREEES and CHARLES S. COURT, citizens of the United States, residing in the city of Providence, in the county of Providence and State of Rhode Island, have invented and produced a new, original, and ornamental Design for the Handle of a Spoon or Similar Article, of which the following is a specification, reference being had to the accompanying drawings, forming part thereof, on which—

A designates the head-section, and B the shank-section, of the handle.

The leading feature of our design consists in the arrangement of apple-blossoms and leaves represented in relief.

On the obverse face, Figure 1, the ornamentation of section A consists of a large apple-blossom 3, lying on its side and facing across the handle. One of its petals projects upward to form the apex 4. In front of this blossom lies a leaf 5 upon a stem 6 and below it an upward-facing blossom 7, which overlaps the lower petals of the first-mentioned blossom and forms the junction of sections A and B. Supporting the blossom 7 is the stem 8, which extends downward along the margin of section B. Along the opposite margin is

a stem which supports the leaf 9. About midway of section B lies a bud 10, branching from the stem 8 and surmounted by the leaves 11 11. Farther down the handle is a small leaf 12, and at the base are the leaves 13 13, with the bud 14 between them.

On the reverse face, Fig. 2, the ornamentation consists of a marginal line representing apple-tree branches from which at various intervals spring buds, leaves, and flowers, which in the head A form a wreath inclosing a plain surface, at the base of which lies a prominent open blossom upon its supporting-stem. Midway of section B is an upturned bud and at the base of the handle a sprig of leaves.

It is evident that this design is applicable to the handles of forks and similar articles.

Our claim is—

The ornamental design for the handle of a spoon or similar article as herein shown and described.

In testimony whereof we have affixed our signatures in presence of two witnesses.

EUSTACE CREEES.
CHARLES S. COURT.
